PRECIOUS ORE RECOVERY APPARATUS

Herman L. Wick, Des Moines, Iowa

Application July 31, 1939, Serial No. 287,473

4 Claims. (Cl. 209—55)

This invention relates chiefly to the art of recovery of precious metals, such as gold, from undesirable material, such as sand, gravel and like.

5 The principal object of my invention is to provide a method of recovering gold, and especially fine gold, from undesirable foreign materials.

A still further object of my invention is to provide an apparatus for use in the recovery of 10 precious metals that continuously is in operation.

15 A still further object of my invention is to provide an apparatus for use in the field of precious metal recovery machines that is economical in manufacture, simple in design and durable in use.

These and other objects will be apparent to those skilled in the art.

20 My invention consists in the construction, arrangement and combination of the various parts of the device, whereby the objects contemplated are attained as hereinafter more fully set forth, pointed out in my claims and illustrated in the accompanying drawing, in which:

25 Fig. 1 is a side view of my apparatus with sections cut away to more fully illustrate its construction.

Fig. 2 is an enlarged top plan view of the material-receiving, rotatably mounted disc.

30 Fig. 3 is a cross-sectional view of a portion of the disc plate taken on line 3—3 of Fig. 2.

The successful and efficient recovery of precious metals, such as gold, is very difficult and this is especially true of fine or powdered gold. With 35 the use of most equipment, a great amount of gold is lost and not recoverable. The use of mercury, potash and like is old but the method of using such recovery agents is very crude, slow and inefficient.

40 I have overcome such objections by providing an apparatus that will continuously mechanically coat or amalgamate the precious metal to be recovered with the recovery agent, such as mercury or like.

45 Referring to the drawing, I have used the numeral 10 to designate a suitable frame for supporting an inverted hollow cone member 11.

The numeral 12 designates a hollow cone member resting on top of the inverted cone 11 and having its upper end portion cut away to provide an opening 13.

These two cone members 11 and 12 form a hollow housing open at its top and secured by any suitable means to the frame 10.

55 The numeral 14 designates a shaft rotatably

mounted in the bottom end of the cone 11 and extending vertically upwardly within the housing, as shown in Fig. 1. This shaft 14 is designed to be rotated by any suitable prime mover.

The numeral 15 designates a disc plate rigidly secured to the top of the shaft 14, horizontally positioned and in a plane substantially with the top plane of the inverted cone portion 11.

This disc plate 15 is concentrically mounted within the housing and, therefore, is directly below the opening 13 of the housing.

The numeral 16 designates a plurality of elongated scoop members U-shaped in cross section, as shown in Fig. 3. The disc plate 15 is designed to be rotated to the right and these elongated cup trough members have their openings facing the direction of rotation, as shown in Fig. 2. These members 16 may be mounted in any suitable manner or arrangement on the upper surface of the plate 15 but I particularly recommend that they be positioned such as shown in Fig. 2 for best results.

In Fig. 2 I show these elongated scoop members curved longitudinally toward the direction of rotation of the disc and extending in such curved lines forwardly of radial lines of the disc plate in order that they will readily engage any materials dropped on the upper surface of the plate.

The numeral 17 designates a second series of 30 elongated scoop trough members positioned on the upper surface of the plate 15 while the members 16 are more centrally located. These trough cup members 17 also extend toward the direction of rotation of the disc plate, and one of these members 17 is located just to the rear of a member 16, as shown in Fig. 2. The inner end portion of one of these members 17 passes a short distance through the rear of the outer end portion of the scoop member 16 adjacent to it in order that material caught by a member 16 will eventually pass to and into the adjacent scoop member 17. Both ends of the members 16 and 17 are open and each set of members 16 and 17 follow substantially a Loger mechanic curve from 35 the center portion of the disc toward its peripheral. By this arrangement the members 17 will extend at a greater angle to a radii line of the disc plate than will the scoop 16 disc to it.

These members 16 and 17 may be secured to 50 the plate 15 by any suitable means, such as soldering, brazing, welding or like 18.

The numeral 19 designates a material feeding pipe extending through the opening 13 and terminating through the dead center top of the 55

plate 15. The ore, gravel, sand, precious metal and like is all fed through this pipe 19 onto the plate 15.

The numeral 20 designates a small pipe extending through the opening 13 and terminating above the plate 15. This pipe 20 is in communication with a suitable source of mercury or other desirable coating or amalgamating material.

The numeral 21 designates an outlet pipe communicating with the inside bottom of the hollow inverted cone 11.

To use my device, it is merely necessary to rotate the shaft 14, inject the mass in which the precious metal resides onto the plate through the pipe 19, and inject the coating or amalgamating agent onto the plate 15 through the pipe 20. If the agent used is mercury, the same will obviously engage the inner sides of the members 16 and 17 and will slowly move from the members 16 and 17 by centrifugal force. By making the members 16 and 17 of copper or like material, the mercury will coat the inner sides of the members 16 and 17. As both the agent and the mass of material is fed to the center portion of the plate 15, both the agent and the mass of material will be caught by the members 16 and 17 and will by centrifugal force, slide outwardly within the members 16 and 17 until the same has cleared the plate. Obviously, this material will be first caught by the member 16 and from the member 16 it will move into and be engaged by the member 17.

Due to the curve and the singularity of the members 16 and 17, the material will slowly move by a scraping action on the inner sides of the members 16 and 17 until the same has cleared the rotating disc plate. As sand, gravel and other like foreign materials will not adhere to mercury and like agents, the same will not be affected by the agent. On the other hand, gold will readily adhere to and is capable of being coated by a mercury or like agent. By the mechanical action of the device, the gold and mercury will be forced together during its time on the disc plate and the gold will either be amalgamated with the agent or will be coated. With the inner sides of the members 16 and 17 coated with the mercury, the small particles will scrape the inner sides of these members and thereby automatically and mechanically coat themselves and amalgamate themselves with the agent. With the particles of gold and mercury clinging together, the same with the mass of undesirable material will pass through and out of the pipe 21.

Various types of equipment now on the market can then be used to recover the mercury and thereafter the separation of the gold from the mercury. The mercury is thus saved and the gold retrieved from the mercury. Even the small particles of gold that are coated with the mercury will be of sufficient weight to be recoverable by standard equipment now on the market.

From the foregoing, it will readily be seen that I have provided a highly desirable apparatus and method for the recovery of precious metals, such as gold.

Some changes may be made in the construction and arrangement of my improved precious

ore recovery apparatus without departing from the real spirit and purpose of my invention, and it is my intention to cover by my claims any modified forms of structure or use of mechanical equivalents which may be reasonably included within their scope. 5

I claim:

1. In a device of the class described, a rotatably mounted member, and an elongated scoop cup member extending along the surface of said first mentioned member in a direction at an angle to the radii of said member; said scoop cup member also extending longitudinally in a curved path and curved in cross section with its open side extending in the direction of rotation of said first mentioned member, an operating conduit terminating above said first mentioned member, and a precious metal adhering agent supply pipe terminating above said first mentioned member. 10

2. In a device of the class described, a rotatably mounted member, a plurality of elongated scoop members extending along the surface of said first mentioned member in a direction at an angle to the radii of said member; each of said scoop members extending in a curved path and being 15 curved in cross section, a means for supplying material to said first mentioned member, and a second means for supplying a precious metal adhering agent to said first mentioned member. 20

3. In a device of the class described, a rotatably mounted member, an elongated member cup-shaped in cross section on said first mentioned member and positioned near its outer portion; said elongated member extending in a direction at an angle to the radii of said rotatably mounted 30 member, and a second elongated member cup-shaped in cross section on said first mentioned member and positioned near its center portion with its outer end slightly forward of and emptying into the rear end portion of said first mentioned elongated member; said second elongated member extending in a direction at an angle to the radii of said rotatably mounted member. 35

4. In a device of the class described, a frame member, a rotatably mounted plate on said frame, a plurality of elongated fins cup-shaped in cross section on the outer portion of said plate having their sides opening in the direction of rotation of said plate and at right angles to said plate with each of said fins longitudinally extending in a direction at an angle to the radii of said plate, a second plurality of elongated fins cup-shaped in cross section on the central portion of said plate of a shorter length than said first mentioned fins and having their sides opening in the 45 direction of rotation of said plate and at right angles to said plate with each of said fins longitudinally extending in a direction at an angle to the radii of said plate, a supply conduit having one end in contact with a suitable source of precious mineral bearing material and its other end terminating above said plate, a second conduit having one end in contact with a suitable source of amalgam and its other end terminating above said plate and said elongated fins having their 50 lengths curved and extending at an angle to the radius of said plate. 55

5. In a device of the class described, a frame member, a rotatably mounted plate on said frame, a plurality of elongated fins cup-shaped in cross section on the outer portion of said plate having their sides opening in the direction of rotation of said plate and at right angles to said plate with each of said fins longitudinally extending in a direction at an angle to the radii of said plate, a supply conduit having one end in contact with a suitable source of precious mineral bearing material and its other end terminating above said plate, a second conduit having one end in contact with a suitable source of amalgam and its other end terminating above said plate and said elongated fins having their 60 lengths curved and extending at an angle to the radius of said plate. 65
